FLUID PUMP AND DRIVE MEANS THEREFOR

Wilhelm König, Frankfort-on-the-Main, Germany, assignor to Alfred Teves Maschinen- & Armaturenfabrik G. m. b. H., Frankfort-on-the-Main, Germany

Application February 6, 1933, Serial No. 655,327
In Germany March 3, 1931

20 Claims. (CL 230—55)

This invention relates to fluid pumps and compressors and to driving means therefor. More particularly it concerns itself with an improved compressor adapted to be directly actuated 5 electro-magnetically by a rectilinearly reciprocable armature forming part of an improved magnetic motor. The invention further contemplates the provision, in combination with such a compressor, of a magnetic motor incorporating 10 an armature whose natural period of oscillation is normally in resonance with the pulsating or alternating current by which the motor is energized, whereby the inertia of the moving parts is utilized to assist in driving the piston of the 15 compressor, and the power applied is expended only in overcoming friction and air resistance once the compressor is in motion.

An important object of the invention is also the provision of means for damping or controllingly restricting the amplitude of the oscillations of the reciprocating parts when they approach dangerous proportions, and for automatically proportioning such damping to the extent to which the amplitude of the oscillations 25 exceeds a desired maximum, thus preventing injury of the reciprocating parts.

A further object is the provision of means for temporarily relieving the load on the compressor if it should become so great as to limit the travel 30 of the reciprocating parts beyond a desirable point, and for automatically controlling the extent of the relief which this portion of the apparatus effects in proportion to the degree of overloading.

Another object is the provision of means for 35 constantly providing and automatically regulating an imposed controlling back pressure adapted to restrict the travel of the piston and the other reciprocating parts sufficiently to prevent the building up of oscillations of dangerously high amplitude, and in which such back pressure is varied in proportion to the extent 40 to which the travel of the reciprocating parts exceeds the desired maximum.

Still another object is the provision of improved mounting means for supporting such a magnetically reciprocable compressor in a manner adapted to utilize in addition to the inertia 45 of the reciprocating parts, the inertia of the body of the device and the thrust imparted thereto by reaction from the force applied to the piston-connected reciprocating parts.

A still further object is the provision in such 50 a reciprocating compressor-motor assembly having oscillatable parts adapted to function in

resonance with the actuating current, of means for limiting the oscillating travel of the reciprocating parts against undesirably great amplitude without imposing additional back pressure 60 upon the compressor except during those periods when such restriction is needed, and without varying the electrical efficiency of the magnetic driving means.

Still another object is the provision in such 65 a compressor and motor unit of slightly modified form, of means for preventing oscillations of undesirably great amplitude and controlling the travel of the parts by automatic proportional variation of the electric current made effective to energize the electro-magnetic driving means.

Other objects and advantages will be apparent 70 from the following description, wherein reference is made to the accompanying drawings illustrating preferred embodiments of my invention, and wherein similar reference numerals designate 75 similar parts throughout the several views.

In the drawings:

Figure 1 is a diagrammatic view schematically 80 illustrating a compressor and motor system incorporating the principles of this invention;

Figure 2 is a horizontal section, partly in plan, 85 of a practical form of compressor and driving unit constructed in accordance with the invention;

Figure 3 is a vertical sectional view thereof 90 taken substantially on the line 3—3 of Figure 2 and looking in the direction of the arrows;

Figure 4 is a fragmentary sectional view similar 95 to Figure 2, showing a somewhat modified form of the invention;

Figure 5 is a similar fragmentary view showing another modified form; and

Figure 6 is a similar fragmentary sectional view 100 of another embodiment.

Referring first to the diagrammatic Fig. 1 of 105 the drawings, E represents an electromagnet, the winding W of which is connected to the terminals of a source of alternating current. The armature M is supported upon springs F which permit it to oscillate toward and from the magnet, and by their characteristics invest the armature with a natural period of oscillation. The piston of a compressor K is shown connected to the armature. The springs F can be sized that the natural period of oscillation of the armature is equal 110 to the number of cycles of the current. In order to obtain the exact energization, one can either use an interrupter cutting one half wave of the current so that the back stroke of the armature is not braked,—or the armature itself might com-

- prise a permanent magnet which in the course of one cycle is once attracted and once repelled. However, both constructions are not very advantageous for the contacts would wear and the magnet lose its efficiency in course of time. In the present invention these disadvantages are eliminated by the arrangement of springs imposing on the armature a natural period of oscillations, which is twice the number of cycles of the alternating current. So it is obtained that during the maximum of the positive and negative wave the armature moves towards the magnet, while the back movement takes place when the current passes its zero points.
- 15 The resonance of the system can be controlled either by varying the masses of the reciprocating parts and so their inertia until the largest possible amplitude is obtained, or by changing the spring resistance.
- 20 Balancing to resonance can also be effected with the aid of the compressor piston. The manner in which this takes place is explained in detail as follows: If a tightly sealing piston is forced into a completely closed cylinder which is filled 25 with gas, the entrapped gas is compressed and exerts a force outwardly which increases with the distance that the piston is removed from its initial position. If the piston is then released, it is returned to its initial position under the influence 30 of the enclosed compressed gas. It acts therefore just like any other spring. The force which is exerted on the piston at any particular position thereof may easily be regulated to a desired magnitude by varying the pressure at the beginning 35 of the inward movement of the piston or by varying the length of the cylinder or, more accurately, the distance of the initial position of the piston from the cylinder bottom. If, for example, the 40 pressure in the cylinder is high at the beginning of the inward movement of the piston, then the pressure will rapidly increase upon further movement of the piston, and the force which is exerted outwardly is correspondingly increased. The same is true if the piston is close to the cylinder bottom at the beginning of its movement. In 45 this case, too, the pressure will increase rapidly upon a slight inward movement and the piston will exert a large force outwardly. It is thus clear that a piston disposed in a gas filled cylinder acts 50 like a spring, the strength of resilience of which can be accurately adjusted by suitably selecting the distance of the piston from the cylinder bottom and by suitably selecting the pressure. A piston of this character may also be conveniently 55 used to regulate the springiness needed for resonance. It has been found that it is not necessary to supplement the steel springs of the present compressor with a special resilient piston, since the compressor piston itself involves a resilience, 60 the temper of which depends directly upon the pressure. The springy action of the compressor piston arises in the following manner: With usual piston compressors, it is endeavored to have the piston move as closely to the cylinder cover as possible in order to expel the compressed gases as completely as possible. In the 65 present compressor, the end position of the piston is so adjusted that the piston does not move quite up to the cylinder cover so that, after completion of the expelling stroke a certain quantity of gas remains in the clearance space of the cylinder, which upon expansion forces the piston outwardly. The compressor piston thus 70 acts as a spring and may therefore be used in establishing resonance. For this purpose, springs f

of Fig. 1 of the oscillating system are selected so that they do not of themselves establish resonance, and the compressor when operating under no load is out of tune to such extent that an excessive amplitude of vibration cannot occur. The clearance space of the piston is so designed that, when the operating pressure is reached and with it a complete damping of the oscillating system, the supplementary piston spring action due to the pressure now present, supplements the action of the steel springs to such extent that resonance is now completely established. By properly dimensioning the compressor cylinder relative to the oscillating mass, it is possible to obtain a supplementary spring action adapted to harmonize or synchronize the system in a very simple manner.

80 The succeeding figures of drawings illustrate structures constituting practical working embodiments of the invention. In these references character 1 designates a box-like housing, preferably of metal and completely enclosed, (when the cover 2 is in place) save for the inlet 3 and outlet 4. The tightly fitting cover plate 2 is shown held in place by screws 5, and between it and the casing 100 may be arranged a sealing gasket 6. One end of the housing carries a projecting boss portion 7 in which is formed a cylinder 8, within which is reciprocable a piston 9 adapted to be driven by an armature 10, to which it is articulated by means 105 of a connecting rod 11. The connecting rod is preferably affixed to both the piston and armature by means of ball and socket or other universal joints, as 12-12', which prevent imposition of lateral stresses upon piston and cylinder 110 walls in event of any irregularities of movement of the armature. The armature is rigidly secured to the core portion 13, and the latter may be of the well known laminated and preferably soft iron, built up construction shown, although this is 115 of course entirely optional. Preferably however the core portion 13 constitutes but a part of, preferably substantially half, the core of the solenoid 15 within which it slidably fits, the other half 14 of the core being of similar construction but 120 fixed with respect to the winding and the housing 1. The abutting ends of the core sections 13-14 are arranged as close together as the reciprocation of the former will safely permit. Both the solenoid and the fixed core section are 125 shown secured in position in the housing by means of a bracket 16, bolted to the floor of the housing as by screws 17 and arranged to support one end of each of the springs 18, which controlling restrict movement of the armature and give 130 it a natural period of oscillation, in the manner previously described. At its other end each spring is secured to and supports one end of the armature 10. In the constructions shown the springs 18 are axially outturned and threaded at their 135 ends, which are passed through suitable apertures (undesignated) in the bracket 16 and armature, and carry nuts 40 on both sides of each of the latter, by adjustment of which nuts the 140 positioning of the armature, piston and movable core may be regulated. The springs are so tuned, and the masses of the reciprocating parts so proportioned thereto that the natural frequency of the oscillating system comprising the springs, armature, piston and connecting parts is in tune with the frequency of the current by which the solenoid is to be energized. The solenoid may be electrically connected to binding post terminals 19, which as shown in Figure 2 project through

the casing, but are insulated therefrom as by bushings 20.

- The compressor inlet 3 may open directly into the casing 1, as shown, and valve ports 21 may 5 be formed in the head of the piston which are normally closed on the compression stroke by a pair of flap valves formed of a single metallic strip, as 22, which may be of spring metal and secured to the piston by means of a screw 23. 10 Between the head 24 and cylinder 8 is arranged a supporting plate 25 for the outlet valves. The latter may be constructed similarly to the valves in the piston, and comprise ports 26 extending through the plate and normally closed during 15 the reverse stroke of the piston by flap valves formed of a spring metal strip 27 centrally secured to the plate as by screw 28 and projecting over both of the ports 26.

From the head 24 an outlet passage 29 runs, 20 through the casing, to an annular chamber 30 formed, as best shown in Figure 2, as an annular groove in one face of the casing body. This chamber is completed and normally closed by a diaphragm 31 held in place by the securing flange 25 32 of a supplementary cylindrical housing 33 for the compression spring 34, which urges the diaphragm against the edges of the groove 30 to yieldably close the annular chamber, and also closes the open end portion 35' of the passage 35 30 which forms a continuation of the outlet passage 29 and opens in the same face of the casing as does the annular groove 30, and inside the area bounded by the same, although it will be seen that communication between the sections 29—35 of 35 the outlet passage is normally sealed by the diaphragm 31, save when the compressor is generating sufficient pressure to unseat it. The spring 34 and diaphragm thus serve to prevent compressed fluid from flowing beyond the chamber 30 until a predetermined pressure has been attained, and so insure a predetermined minimum back pressure. The capacity of the outlet passage 29 and chamber 30 is so small that sufficient back pressure is built up to prevent the piston 40 from striking the valve plate, and the building up of oscillations of dangerous amplitude, before such oscillations have attained even their normal operating amplitude. The spring 34 is shown as adjustable in tension by means of the combined 45 abutment plate and adjustment screws 37, which may be locked in position by means of a jam nut 38.

However, it is also possible to omit diaphragm 31, Fig. 2, and the other associated parts, and to 55 withdraw the compressed gas directly from the cylinder cover 24, if springs 18 are so designed that they cannot by themselves synchronize to resonance and if the distance of the piston from the valve plate 25 as well as the diameter thereof 60 are such, relative to the normal pressure, that the piston spring action which appears with increasing pressure brings about synchronization to resonance in the manner hereinbefore described. The machine will then assume the appearance shown in Fig. 3.

Preferably the casing is mounted in such manner that it is free to move laterally and oppositely under the successive reactive impulses imposed upon it each time the armature is driven 70 in either direction by the springs and solenoid. It is shown mounted on springs 41, the main purpose of which is to permit free lateral movement of the housing, although they of course also prevent undue transference of vibrations to 75 the base or other support on which the device

is mounted, after the fashion of the cushioning devices commonly used under compressors. In place of such springs, any other mounting permitting the casing free lateral movement might be used, as tracks upon which the casing might roll or slide, or rollers or wheels alone. It has been found that provision of this means whereby free reactive travel of the casing is possible produces very efficient operation of the machine and full utilization of the forces generated.

In Figure 4 is shown a somewhat modified construction in which the electro-magnetic motor and compressor may be generally of like construction however to those just described, like parts being designated by similar reference characters one hundred integers higher. In place of a pair of valves in the valve plate 125, a single centrally located valve port 126 may be employed, normally closed during the down stroke of the piston by the spring leaf flap valve 127. Two valve ports 121 are provided in the piston in like manner to the ports 21 in the first described embodiment, but the head of the screw 123 by which the valve member 122 is secured to the piston is of such size and so positioned as to slide within the port 126 as the piston approaches the end of its compression stroke, thereby closing or partially closing the space between the piston head and valve plate and trapping a quantity of the fluid being pumped therein to serve as a cushion.

The outlet passage 129 extends from the head 124 to an annular chamber 130, similarly arranged to the chamber 30 previously described, and communication between such chamber and the outlet continuation 135 is normally yieldably closed by a diaphragm 131, pressed by the spring 134 against the wall separating the annular chamber 130 and the portion 135' of the continuation 135, which opens in the same wall of the casing 101 as does the annular chamber 130, and inside the latter in like manner.

The spring 134 is relatively much weaker than analogous spring 34 of the previously described embodiment, however, and does not hold the diaphragm in outlet-closing position with force enough to create sufficient back pressure to prevent the building up of oscillations of unduly great amplitude by the reciprocating parts. The spring housing 133 is hermetically sealed, as by means of the cap 136, and provided with an inlet passage 45 connected to the outlet 129 of the pump. This passage is normally closed by a valve 46, which is held closed by the outlet pressure augmented by a spring 47. Valve 46 is adapted to be intermittently lifted by an adjustable stop 48 carried by the armature when and only when the latter moves farther in its oscillating travel than the desired maximum amplitude. When this occurs the stop 48 contacts the valve stem 46', which extends into the inlet chamber of the housing to a point in proper proximity to the stop, (as shown in Figure 4). The stem 46' preferably fits tightly in the guide 49 to prevent leakage from the outlet to the inlet therealong. It will be seen that when the valve 46 is so intermittently opened by unduly extensive oscillations of the armature, fluid from the outlet under pressure is admitted to the chamber 133 behind the diaphragm 131 to augment the spring 134 and so force the diaphragm more tightly against its seat and close the outlet more firmly, thus building up greater back pressure in the chamber 130 and connected outlet, which such back pressure

not only tends to dampen the oscillations of the 140 145 150 155 160 165 170 175 180 185 190 195 200 205 210 215 220 225 230 235 240 245 250 255 260 265 270 275 280 285 290 295 300 305 310 315 320 325 reciprocating parts, but acts as additional resili-
ent resistance, thus de-tuning the system so
that they die away in amplitude until stop 48
no longer lifts the valve 46, after which the pres-
sure in chamber 133 is gradually relieved by es-
cape of fluid therefrom through the connected
bleeder passage 50 and bleeder valve 51 to the
inlet or spring chamber of the housing. The
communication furnished through the bleeder
valve and passage is of course insufficient, how-
ever, to prevent the building up of the augment-
ing pressure in the spring chamber when the
valve 46 is being opened in the manner described.
It will be seen that by virtue of this arrangement,
when the pump is operating under a properly
proportioned load and the valve 46 remains
closed, the back pressure in addition to that
caused by the normal working of the compressor
generated by the spring 134 is but slight, while
if the work demanded by the compressor falls
off unduly and the amplitude of the oscillations
resultantly increases dangerously, valve 46 is im-
mediately actuated and the strength of the spring
134 augmented to close the outlet more tightly
and increase the back pressure until the oscilla-
tions have been damped to a safe amplitude.

Figure 5 shows another somewhat modified
method of controlling the oscillations of the re-
ciprocating parts, comprising a choke coil 55
having a core portion 56 slidable partially out of
the choke, the winding of which is arranged in
series with the solenoid 215 of the magnetic
motor, as shown. A passage 229 connected to the
outlet 235 of the pump extends to a chamber 230,
one wall of which is formed by a flexible dia-
phragm 231 held in place by the bracket 232 which
supports the choke coil. The diaphragm is con-
nected to the movable core section 56, as by the
link 57, and these parts are so arranged that when
the diaphragm is relaxed the core is completely
within the choke, and so the reactance of the
latter is at its maximum; the effect of course
being to cut down the efficiency of the solenoid
215 to that extent. When the compressor is
running, however, the pressure in chamber 230
is raised by reason of its connection with the
pump outlet 235, and this pressure is sufficient
under normal pump operation to move the dia-
phragm and so the core 56 sufficiently so that the
latter is out of the choke far enough to prevent
its interfering materially with the current to the
solenoid. The by-pass connection between the
outlet-connected chamber 230 and the main inlet
chamber of the casing 201 in which the arma-
ture is housed, is provided by a passage 58 con-
necting these chambers but normally closed by a
valve 246 yieldably held seated by the pressure
in chamber 230 augmented by the force of spring
247. The valve stem 246' projects into the inlet
chamber to a point adjacent the stop 248, which
is so adjusted as to contact the same only when
the armature stroke exceeds the desired maxi-
mum, at which time it intermittently lifts the
valve 246, relieving the pressure in the chamber
230 and so allowing the diaphragm to relax and
draw the core into the choke, cutting down the
efficiency of the solenoid 215 and so reducing the
power of the magnetic motor and the amplitude
of the oscillations of the reciprocating parts. A
metering valve as 59 in the passage 229 prevents
the inflow of fluid to chamber 230 faster than the
valve 246 can relieve the pressure when the latter
is actuated by excessive oscillating travel of the
armature.

It will be observed that in the embodiments

shown in Figures 2, 3 and 4, the efficiency of the
compressor is somewhat reduced (although but
slightly in the embodiment shown in Figure 4)
by the back pressure created by the diaphragm
(31-131) in the outlet; and that in the embodi-
ment shown in Figure 5 the electrical efficiency of
the magnetic motor is likewise at times limited to
prevent unduly extensive travel of the reciprocating
parts. In Figure 6, however, is shown an em-
bodiment in which neither the mechanical effi-
ciency of the compressor nor the electrical effi-
ciency of the magnetic motor are at any time
interfered with, although effective means is pro-
vided for preventing oscillations of unduly great
amplitude. This arrangement is such that upon
the oscillations of the reciprocating parts exceed-
ing the desired maximum, the oscillating system
is thrown slightly out of resonance, and is held
in that condition while the oscillations die to safe
proportions, after which the resonant condition
is restored and the operation may resume in the
normal manner.

The entire unit is of course preferably so de-
signed that the parts may oscillate in resonance
when the compressor is under normal load. To 100
throw the system out of resonance when the oscilla-
tions of the armature 310 reach undesirable
proportions, a pair of springs 60 are provided,
each attached at one end to the armature 310,
as by screws 61, and at the other to a piston rod 62. 105
Each piston rod carries a piston 63 reciprocable
in an auxiliary cylinder 64 formed in the side of
the casing 301 substantially in axial alignment
with the central positioning of the spring 60.
Leather gaskets, as 65, 66, seal the chamber 67 110
beneath the piston, and to this chamber leads a
passage 68 connected through a valve 346 to a
source of fluid supply under pressure (not shown)
which may comprise the outlet 335 of the pump,
although no connection thereto is shown. The 115
valve stem 346' extends into the inlet chamber
of the casing to a point in such proximity to the
armature-carried stop 348 that the latter inter-
mittently lifts the valve whenever the travel of
the armature becomes unduly extensive, thus ad-
mitting fluid under pressure to the chamber 67 120
to move the piston outwardly, stressing the spring
60 and so detuning the oscillating system as to
throw it out of resonance. Preferably two such
spring and piston assemblies are used, as shown, 125
(although but one is broken away to sectionally
illustrate it in detail).

The oscillating system of this embodiment is
of course tuned with the spring 60 relaxed, so
that the parts tend to reciprocate in resonance 130
with the current only when the pistons 63 are
indrawn by such springs. It will further be noted
that the aperture in the casing 301 through which
the piston rod 62 extends into the chamber 67
does not fit the piston rod snugly, and as the 135
leather gasket 65 does not constitute an hermetic
seal, after the oscillations of the reciprocating sys-
tem have died down to safe proportions as a re-
sult of the detuning of the oscillating system, the
fluid admitted to the chamber 67 during actuation 140
of the valve 346 may bleed through the valve and
along the piston rod back to the inlet chamber,
and so permit the piston to move inwardly and the
springs 60 to relax, when resonant oscillation can
be reestablished.

While it will be apparent that the illustrated
embodiments of my invention herein disclosed are
well calculated to adequately fulfill the objects
and advantages primarily set forth, it is to be
understood that the invention is susceptible to 145

variation, modification and change within the spirit and scope of the subjoined claims.

What I claim is:

1. In combination with a source of pulsating electric current of substantially fixed frequency, 5 a solenoid energizable by the same, an armature actuatable by the solenoid, a pump having a piston connected to the armature, means yieldably restraining the armature from movement and imparting a fixed natural period of oscillation thereto which is substantially in tune with energization of the solenoid, and means preventing the oscillations of the armature from reaching an amplitude at which the armature might strike 15 against any other part.
2. In combination with a source of pulsating current of predetermined frequency, a solenoid energizable thereby, an oscillatable armature actuatable by the solenoid, a pump including a piston connected to the armature for simultaneous reciprocation, resilient means imposing upon the armature a period of oscillation in tune with energization of the solenoid, and means for artificially increasing the back pressure of the pump 20 to prevent reciprocable parts from oscillating at undesirably high amplitudes.
3. In combination with a source of pulsating current of predetermined frequency, a solenoid energizable thereby, an oscillatable armature actuatable by the solenoid, a pump including a piston connected to the armature for simultaneous reciprocation, and resilient means so yieldably restraining movement of the armature as to impose thereupon and upon the piston a natural period of oscillation double the number of cycles of 35 energizing current.
4. In combination with a source of electric current of predetermined frequency, an electromagnetic winding adapted to be energized thereby, an armature reciprocable by such electromagnet, a pump having an outlet and including a piston connected to the armature for simultaneous reciprocation, resilient means imposing upon the armature a period of oscillation in tune with energization of the solenoid, means for increasing the back pressure of the pump to prevent oscillations of undesirably high amplitudes, including a pressure member yieldably obstructing the outlet, and means for increasing the tension with 40 which such obstruction is maintained, comprising means for connecting the output of the pump to a chamber behind the pressure member, and means for opening said connecting means when oscillations of the reciprocating parts exceed a desired maximum.
5. In combination with a source of electric current of predetermined frequency, a solenoid winding energizable thereby, an armature reciprocable by the solenoid, a pump having an outlet and a piston connected to the armature for simultaneous reciprocation, resilient means imposing upon the armature a period of oscillation in tune with energization of the solenoid, means for increasing the back pressure of the pump to prevent oscillations of undesirably high amplitudes, including a spring-pressed member obstructing the outlet.
6. In combination with a source of electric current of predetermined frequency, a solenoid winding energizable thereby, an armature reciprocable by the solenoid, a pump having an outlet and a piston connected to the armature for simultaneous reciprocation, resilient means imposing upon the armature a period of oscillation in tune with energization of the solenoid, means 70 for increasing the back pressure of the pump to prevent oscillations of undesirably high amplitudes, including a member adapted to obstruct the pump outlet and movable to offer more or less obstruction, pressure operable means for urging said member toward a position of greater obstruction, and means responsive to oscillations of the reciprocating parts of greater than a predetermined amplitude for rendering said fluid pressure means operative.
7. In combination with a source of electric current of predetermined frequency, a solenoid winding energizable thereby, an armature reciprocable by the solenoid, a pump having an outlet and a piston connected to the armature for simultaneous reciprocation, resilient means imposing upon the armature a period of oscillation in tune with energization of the solenoid, means for increasing the back pressure of the pump to prevent oscillations of undesirably high amplitudes, including a member adapted to restrict the pump outlet and movable toward and from restricting position, the tendency of the output of the pump being to move said member away from restricting position, fluid-pressure actuatable means for urging said member toward restricting position, means connecting the pump output to said last-named means, valve means controlling said connection, and means for opening said valve in response to oscillations of the reciprocating parts of an undesired amplitude.
8. In combination with a source of pulsating electric current of predetermined frequency, a solenoid energizable thereby, an armature reciprocable by the solenoid, a pump having an outlet and a piston connected to the armature for simultaneous reciprocation, resilient means impressing upon the armature a period of oscillation in tune with the energization of the solenoid, variable means for controllingly reducing the effective current by which the solenoid is energized, and means responsive to oscillations of the reciprocating parts of undesired amplitudes for actuating said current controlling means.
9. In combination with a source of electric current of predetermined frequency, a solenoid winding energizable thereby, an armature reciprocable by the solenoid, a pump having an outlet and a piston connected to the armature for simultaneous reciprocation, resilient means imposing upon the armature a period of oscillation in tune with energization of the solenoid, and means for preventing oscillations of the reciprocating parts of greater than a predetermined amplitude, comprising controllably variable means for impairing the current to the solenoid, pressure-responsive controlling means therefor connected to the pump outlet and normally held thereby in a position in which the former interferes to a minimum with the current to the solenoid, means operable in response to a predetermined degree of movement of a reciprocating part for relieving the pressure affecting said actuating means to resultantly vary the current energizing the solenoid to reduce the output thereof and so the severity of actuation of the armature.
10. In combination with a source of pulsating electric current of predetermined frequency, a solenoid adapted to be energized thereby, an armature reciprocable by the solenoid, a pump having a piston connected to the solenoid for simultaneous reciprocation therewith, resilient means impressing upon the reciprocating parts a period of oscillation in tune with energization

- of the solenoid, and means responsive to the amplitude of the reciprocations of the armature for varying said resilient means to detune the system to limit the amplitude of the oscillations.
11. In combination with a source of pulsating electric current of predetermined frequency, a solenoid energizable thereby, an armature actuatable by the solenoid, a pump including a piston reciprocable by the armature, resilient means imposing upon the armature a natural frequency of oscillation in tune with energization of the solenoid, and means responsive to the amplitude of the reciprocations of the armature for varying the effective resiliency of said resilient means to detune the oscillations thereof upon exceeding a desired maximum amplitude. 80
12. In an electromagnetic motor, a reciprocable armature, a solenoid winding, a core section of magnetic material therewithin and occupying only a part of the space within the solenoid, another core section abutting the first adapted to cooperate therewith and movable axially of the solenoid, means connecting the armature and said last named core section, resilient means connected with the armature providing a natural periodic oscillation frequency, and supplemental resilient means comprising a fluid compression chamber for opposing excessive oscillation amplitude. 85
13. In an electromagnetic motor, a source of energy comprising an alternating electric current, electromagnetic driving means comprising a solenoid energized by said current, a core section fixed relatively to the solenoid and occupying only a part of the space therewithin, a reciprocable armature including a complementary core section forming with the first mentioned section a substantially complete core but movable relatively to the solenoid and first section in resonance with said current. 90
14. In combination with a source of pulsating electric current of predetermined frequency, an electromagnetic motor energizable thereby and including a reciprocable armature, a cylinder, a piston drivable by the motor, resilient means restraining movement of and imposing upon the armature a natural period of oscillation approximately in tune with the impulses imparted to it, and means for controllingly imposing a back pressure upon the piston to vary the restraining forces acting thereupon and upon the armature and thereby tune the oscillating system. 95
15. In combination in an electromagnetically driven reciprocating compressor, an electromagnet energized by periodically varying current, an armature actuated by said electromagnet, a compressor comprising a cylinder and a piston, said piston being connected to said armature and actuated thereby, said piston and armature constituting together a reciprocating unit having resilient means impressing thereon an oscillatory frequency corresponding to the periodic variations of the current, said cylinder having a fluid outlet and said piston having means for closing said outlet upon reaching a predetermined position spaced from the end of the cylinder whereby upon further movement of the piston a resilient fluid cushion is established which opposes oscillations of said unit of excessive amplitude. 100
16. In combination in an electromagnetically driven reciprocating compressor, an electromagnet energized by periodically varying current, an armature actuated by said electromagnet, a compressor comprising a cylinder and a piston, 105
- said piston being connected to said armature and actuated thereby, said piston and armature constituting together a reciprocating unit having resilient means impressing thereon an oscillatory frequency corresponding to the periodic variations of the current, said outlet opening into a discharge conduit, means actuated by the outlet pressure for obstructing the outlet passage, means controlled by the amplitude of the oscillations of said unit for rendering said obstructing means effective, said piston having means for closing the outlet from the cylinder upon reaching a predetermined position whereby a resilient fluid cushion is established which opposes oscillations of said unit of excessive amplitude. 110
17. In combination in an electromagnetically driven reciprocating compressor, an electromagnet energized by periodically varying current, an armature actuated by said electromagnet, a compressor comprising a cylinder and a piston, said piston being connected to said armature and actuated thereby, said piston and armature constituting together a reciprocating unit having resilient means impressing thereon an oscillatory frequency corresponding to the periodic variations of the current, said resilient means comprising steel springs which impose on the system a natural period of oscillation which is so different from the energizing frequency that the amplitude 115 remains less than a certain amount as long as the compressor has no back-pressure to overcome, a resilient device comprising the piston and cylinder, and means for varying the resilience of said device, whereby the reciprocating unit is synchronized to resonance with the periodically varying current. 120
18. In combination in an electromagnetically driven reciprocating compressor, an electromagnet energized by periodically varying current, an armature actuated by said electromagnet, a compressor comprising a cylinder and a piston, said piston being connected to said armature and actuated thereby, said piston and armature constituting together a reciprocating unit having resilient means impressing thereon an oscillatory frequency corresponding to the periodic variations of the current, said resilient means comprising steel springs, which impose on the system a natural period of oscillation which is so different from the energizing frequency that the amplitude remains less than a certain amount as long as the compressor has no back-pressure to overcome, a control cylinder, a cushion produced by gases enclosed in said control cylinder, 125 said cylinder permitting the cushioning effect of the gases contained therein which, with complete counterpressure, is of such magnitude that synchronization to resonance results. 130
19. Compressor drive comprising means forming an alternating magnetic field, an oscillating system under the influence of said field and having an oscillatory frequency in tune with the field, a compressor, and a driving connection between said system and said compressor, said connection comprising a thrust rod and means providing for slight pivotal movement thereof. 135
20. In combination a compressor comprising a cylinder and a piston reciprocable in said cylinder, means for operating said compressor resonantly, a base, and means supporting said compressor on said base, said supporting means assuring maintenance of resonant operation of the compressor. 140

CERTIFICATE OF CORRECTION.

Patent No. 1,978,866.

October 30, 1934.

WILHELM KÖNIG.

It is hereby certified that error appears in the printed specification of the above numbered patent requiring correction as follows: Page 6, line 40, claim 13, after the word "current" and before the period insert the comma and words , and a fluid compression device connected to the reciprocable armature; and that the said Letters Patent should be read with this correction therein that the same may conform to the record of the case in the Patent Office.

Signed and sealed this 12th day of February, A. D. 1935.

Leslie Frazer

(Seal)

Acting Commissioner of Patents.
